Attorney

UNITED STATES PATENT OFFICE.

EZRA DIXON, OF BRISTOL, RHODE ISLAND.

TOP-ROLL SADDLE.

Application filed February 9, 1925. Serial No. 8,088.

To all whom it may concern:

Be it known that I, EZRA DIXON, a citizen of the United States, residing at Bristol, in the county of Bristol and State of Rhode Island, have invented new and useful Improvements in Top-Roll Saddles, of which the following is a specification.

This invention relates to certain new and useful improvements in top roll saddles, the primary object thereof being to provide improved means for lubricating the back saddle without the customary interference from the extension of the front saddle.

A further object of the invention is to provide means for permitting a supply of lubricant to be easily, quickly and conveniently applied to the saddle.

The invention has still further and other objects which will be later set forth and manifested.

In the drawings:—

Figure 1 is a side elevation of the invention applied to rolls in operative position.

Figure 2 is a top plan view of the back saddle.

Figure 3 is a bottom plan view of Fig. 2 and

Figure 4 is a section on line 4—4 of Fig. 1.

In proceeding in accordance with the present invention, the front saddle 1 has a rear stem or extension 2 formed for removable connection with the back saddle 3 by means of a bifurcated lug 4 disposed centrally of the length of the back saddle.

The upper face of the back saddle is formed with a pair of longitudinal lubricant-receiving cavities 5 and 6, the chambers having their inner ends separated by the lug 4. A lip 7 of dished and semi-circular shape is formed integral with the back saddle and extends outwardly from a side of the back saddle at points around an end of the lug 4 so that when oil is supplied to the center of the lip same will flow into each of the cavities. The cavities have openings 8 and 9, in their bottoms for a purpose now to be described.

The under face of the back saddle is a central longitudinal depending enlargement 10 which latter at one end merges into a cast lateral flange 11 which stiffens the structure and reinforces the enlargement. The

enlargement and flange are perforated to receive a wick 12 the ends of which latter project outwardly beyond the flange and the outer end of the enlargement. The openings 8 and 9 extend into the perforation of the enlargement so that oil placed in the cavities will flow into the wick carrier and thus saturate the wick.

From the foregoing it will be seen that the wick not only uniformly distributes the oil but also constantly feeds same to the rolls, due to the contact of the wick ends with the adjacent opposed rolls.

The oil may be introduced into the lip or spout 7 at the center thereof, or from either side as desired. Since the lip projects outwardly from a side of the back saddle it will be noted that the customary interference of the stem 2, in the prior art, with convenient feeding of the lubricant to the saddle, due to the extension or stem 2 completely covering the back saddle, is entirely overcome.

Having thus described my invention, what I claim as new and desire to secure by Letters Patent, is:

1. In a top roll saddle, a back saddle having a pair of longitudinal lubricant receiving cavities spaced at their inner ends, a longitudinally perforated wick carrier depending from the back saddle, the back saddle having openings leading from the respective cavities into the carrier, a wick in the carrier having its ends projecting therebeyond for engagement with the adjacent rolls, and a substantially semi-circular lubricant conveying spout extending outwardly from a side of the back saddle and having its ends leading into the respective cavities.

2. In a top roll saddle, a back saddle having a pair of lubricant-receiving cavities, a wick carrier on the under side of the saddle, the saddle having openings establishing communication between the cavities and carrier, a wick in the carrier having its ends projecting beyond the carrier ends and a lubricant conveying lip extending outwardly from a side of the saddle and communicating with each of the cavities.

In testimony whereof I have signed my name to this specification.

EZRA DIXON.
